UNITED STATES PATENT OFFICE.

JOHN C. DEAGAN, OF CHICAGO, ILLINOIS.

PERCUSSION MUSICAL INSTRUMENT.

1,369,268.

Specification of Letters Patent: Patented Feb. 22, 1921.

Original application filed August 6, 1917, Serial No. 184,583. Divided and this application filed October 10, 1918. Serial No. 257,619.

To all whom it may concern:

Be it known that I, JOHN C. DEAGAN, citizen of the United States, residing at Chicago, in the county of Cook and State of Illinois, have invented a certain new and useful Improvement in Percussion Musical Instruments, of which the following is a full, clear, concise, and exact description.

My invention relates to percussion musical instruments. The instrument of my invention, includes a plurality of sounding bars capable of producing tones of a chord when set into vibration. In accordance with one feature of the invention the bars are provided with a resonating box having openings therein through which the sound produced by the bars may pass, there being a partition or partitions within the interior of the box that divide the box into resonating compartments, these partitions sloping to have portions thereof underlie the openings pertaining thereto. Each resonating compartment preferably has two valves for adjusting the effective size of the opening therein, one valve being normally fixed while the other is adjustable.

In accordance with another feature of my invention the sounding bars are flat and are supported by strings located near the opposite ends of the bars and at nodal points thereof. These strings pass through openings in the bars and are themselves provided with supports that have string engaging portions located at the spaces between the bars and between the ends of the bars whereby the bars are flexibly supported in substantially the same plane without having freedom for moving materially in their plane.

I will explain my invention more fully by reference to the accompanying drawing showing the preferred embodiment thereof and in which Figure 1 is a front elevation with one of the sounding bars partially broken away to reveal certain characteristics of construction; Fig. 2 is a view on line 2-2 of Fig. 1; Fig. 3 is a view on line 3-3 of Fig. 1; Fig. 4 is a view on line 4-4 of Fig. 1; and Fig. 5 is a plan view of a portion 50 of the instrument, with parts removed.

Like parts are indicated by similar characters of reference throughout the different figures.

Each sound producing device is inclusive 55 of a flat sounding bar 1 and a resonating

compartment 2 longitudinally of which the sounding bar is disposed, the compartment having an opening 3 desirably extending longitudinally of the bar in the space between the nodal points thereof, this opening 60 being narrower than the bar and provided on the side of the compartment which faces the bar. Each bar has an opening 4, at each of two nodal points, that extends from broad face to broad face of the bar and which is 65 preferably rounded at its ends and is smaller at mid length to avoid sharp edges at its ends. The resonating compartments 2 are formed by wall portions of a box 5 whose interior is separated off into tubular spaces 70 by means of partitions 6 which partially underlie the openings 3, these partitions serving not only to separate the box 5 into resonating compartments but also directly acting as sound reflectors which are 75 impinged upon by the sound waves entering the resonating chambers before encountering other walls of the resonating chambers. Sounding bar supporting posts 7 are disposed between the bars and are screwed into 80 the front wall of the box and are provided, each, with four apertures. The two uppermost or outermost apertures in each post are threaded by a string 8 desirably in the form of a leather thong. Each post thus has engagement with the string at places spaced apart longitudinally of each post a distance materially in excess of the thickness of the bars. There are two rows of such posts located in transverse alinement with the openings 4. There is desirably provided one 85 thong or string 8 for the row of posts which is turned upon itself so that both ends of the same string are attached to the same post, the right hand post as exhibited in 90 Figs. 4 and 5, where both ends of the string are tied together in a knot 9. Parts of the string are laced inwardly through the openings 4 and other parts of the string are laced outwardly through these openings, the string 95 being crossed within the openings 4. The bight of the string is anchored to the extreme left hand post 7 as indicated. By this arrangement the bars are flexibly supported in substantially the same plane without 100 having freedom for moving materially in such plane.

I desirably provide a supplemental string cushion 10 in association with the string 8, which supplemental cushion is preferably 110

normally out of contact with the bars but serves to support the bars in the event of breakage of its associate string. In case the string 8 should sag sufficiently to bring the 5 bars in contact with the supplemental cushions 10 the latter cushions may be shifted to thread the openings 11 in the post 7 which are farther away from the bars than the openings through which the strings 10 are 10 initially passed.

Strips 12 are attached to the outer ends of the posts 7 by means of nuts 13, these strips being in the planes of the strings 8 and 10 sufficiently to conceal the same to 15 prevent the strings, particularly the string 8, from being unsightly. The concealing strips 12 are desirably inturned at 14 sufficiently to conceal the places of attachment of the strings 8 and 10 with the outermost 20 posts 7, the inturned ends of the strips 12 being in the same planes with the rows of posts 7.

The bars are preferably, but not necessarily, of uniform length and width but of 25 differing thickness.

In the construction of the instrument each opening 6 is provided with a pair of valves 16 and 17. The valves 17 are arranged to enable them to be adjusted by the user while 30 the valves 16 are fixedly adjusted in the construction of the instrument. The instru-

ment thus leaves the factory accurately tuned and if for any reason the tuning becomes disordered it may be reeffected by the valves 17.

Claims relating to the mounting of the bars are contained in my original application Serial No. 184,583, filed August 6, 1917, of which the present application is a division.

While I have herein shown and particularly described the preferred embodiment of my invention I do not wish to be limited to the precise details of construction shown as changes may readily be made without departing from the spirit of my invention but having thus described my invention I claim as new and desire to secure by Letters Patent the following:—

A musical instrument having a plurality of sounding bars; a box upon which these bars are mounted; openings in the box through which sound may pass; and partitions subdividing the interior of the box into resonating compartments and which partitions slope to have portions thereof underlie the openings pertaining thereto.

In witness whereof, I hereunto subscribe my name this 27th day of September, A. D. 1918.

JOHN C. DEAGAN.
